CODED CONTINUOUS INDUCTIVE TRAIN
CONTROL AND CAB SIGNALING SYSTEM
FOR RAILROADSWade H. Reichard and Charles S. Bushnell,
Rochester, N. Y., assignors to General Railway
Signal Company, Rochester, N. Y.

Application August 30, 1939, Serial No. 292,628

20 Claims. (Cl. 246—63)

This invention relates, in general, to train control systems, and has more particular reference to systems of the coded continuous inductive type, including cab signals and speed control.

One of the objects of the present invention is to provide new and improved suppressive braking means whereby, upon the actual speed exceeding a newly imposed, reduced, limiting speed, a reasonable time is provided for the engineer to apply his brakes and move his master controller handle to the "off" position, in order to thereby forestall an emergency brake application.

Another feature of the present invention is to provide a new and improved pneumatically operated propulsion current cut-out relay.

Another feature of the present invention is to so arrange and circuit the decoding relays employed in the system, as to, in general, make the system quick and sensitive to respond to changes from less to more restrictive conditions, and slow, and less sensitive to respond to changes from more to less restrictive conditions.

Another feature of this invention is to provide means for giving adequate, and arresting, visual and audible indications when the speed limit is being closely approached.

A further object of the invention is to provide improved acknowledging and non-signaled territory controls.

Further objects, purposes and characteristic features of the invention will appear as the description progresses, reference being made to the accompanying drawings, showing, in a wholly diagrammatic manner, and in no sense, whatsoever, in a restrictive way, one form which the invention can assume. In the drawings:

Fig. 1 of the drawings is a diagrammatic representation of one form of the invention and is comprised of the partial Figures 1A, 1B, 1C and 1D assembled with the lower long edge of 1A matching the upper long edge of 1B and the right and the left short edges of 1C and 1D respectively matching the left and right short edges of 1B.

Fig. 2 shows the engineer's brake valve in one of its operative positions.

Referring now to the drawings, there is here shown in a schematic manner, a car equipped with apparatus in accordance with this invention. Each car has a cab at each of its ends, as cab A, and cab B, and is capable of running with either end forward. Much of the apparatus involved in the present invention is included in the designated "Mech. Case and Gov.," which can be conveniently located, is common to the two

cabs, and is employed in connection with each of the cabs.

The equipment peculiar to each cab, is identical in the case of each cab, and accordingly, a description of the equipment in one cab, should largely suffice for the other cab.

Before considering any of the operation of the system in any considerable detail, it would appear in the interest of clarity, to briefly describe the apparatus peculiar to a cab.

Referring now to cab A, shown as "Cut in," as the forward cab, there is here provided an acknowledging contactor Ack. C., which is operable by the engineer by means of a foot pedal; a non-signal contactor N. S. C., which is relatively inaccessible to the engineer, being positioned in the roof of the car outside of the cab door, and operable by the handle of the engineer's brake valve; and a directional switch, Direc. Sw., which is conveniently located for operation by its own handle. The functions performed by these three contactors will appear as the description progresses.

In addition to the above, there is provided in each cab, an engineer's brake valve EBV, which, in the present case, is of the M-24-D type, the feed valve in the branch pipe 65 omitted; and (with the handle latch means, whereby the handle can be removed only when in the "handle off" position, and then only if a full service brake application has been incurred, also omitted) this valve is provided with a special adapter E, involved in the operation of a suppression relay SR. Also, in each cab is a master controller MC, an electro-pneumatic valve EPV, a power-off relay POR, an emergency cut-out valve ECV, an emergency application valve EAV, and a brake pipe cut-out valve BPCV.

Considering the above devices somewhat more in detail, the brake pipe cut-out valve BPCV can be positioned in either of its two indicated positions, "in" and "out." In cab A this valve is shown in its "in" position, wherein the engineer's brake valve EBV is connected to the brake pipe EP, by means of the port 2, the power-off relay POR is connected, by means of pipe 3 to the valve port 4, and thence by means of pipe 5, and the port 6 of the emergency cut-out valve ECV, in its "in" position, to the passage 7 in EPV. This passage 7, with EPV in its energized position, as shown, communicates with a chamber 8, connected, through passage 9 and pipe 10, check valve 11, strainer 12, and pipe 13, to the brake pipe BP. Thus, brake pipe air pressure is con-

nected to the power-off relay, when the brake pipe cut-out valve is in its "in" position.

Brake pipe air pressure is also connected, by means of pipe 14, to the master controller MC.

5 The brake pipe cut-out valve port 15, in communication with atmosphere ATM, by means of pipe 16, is blanked off in this "in" position.

Considering cab B for the moment, the brake pipe cut-out valve BPCV¹ is here in its "out" 10 position, wherein it can be seen that the engineer's brake valve is blanked off from the brake pipe by means of the portion 15¹ of the cut-out valve. Also in this case, the pipe 16¹, connected to atmosphere, is connected through the cut-out 15 valve and pipe 17¹ to the power-off relay POR¹.

Returning to cab A, the master controller MC, 20 controls energy for forward operation of the car, which is electrically propelled. It includes a handle 18, shown in its "off" position, wherein, by means of a key 19 in its "off" position, the handle is held down against the urge of a spring 20, which otherwise would unseat a valve 21, and connect pipe 14 to atmosphere, through a vent 22. When the key is in any other than the "off" 25 position, it is necessary that the engineer constantly keep his hand on the handle, as otherwise the above referred to venting will automatically take place, and as described below, will result in an emergency brake application. The 30 handle rotates a contact carrying drum 23, having contact strips 24 and 25, for purposes to be later described.

The electro-pneumatic valve EPV is of usual 35 construction, and functions as, for example, in the patent to C. F. Estwick, No. 1,704,183, granted March 5, 1929. In general it comprises a casing 26, containing a winding 27, which, when energized, overcomes the influences of springs 28 and 29, and maintains valve 30 in the position as 40 shown in cab A, that is, in a position to blank off the port 31 leading to atmosphere, and interconnect passages 7 and 9 by way of the chamber 8.

When the EPV is deenergized, as is the case with EPV¹ of cab B, valve 30¹ is moved to its 45 upper position, whereby to connect passage 7¹ to atmosphere, and blank off the passage 9¹ from communication with passage 7¹.

The suppression relay SR comprises a casing 32, enclosing a fixed contact 33, and a movable 50 contact 34, which are biased toward open position by a spring 35, operating through an arm 36. It is possible to overcome the effect of spring 35, by means of a pneumatically operating diaphragm 37, controlled by air pressure in a chamber 38, connected by pipe 39, to the adapter E of the engineer's brake valve EBV.

The emergency cut-out valve ECV can be moved to either of its two positions "in" or "out," and in cab A, and as well in cab B, it is shown in its "in" 60 position, wherein air pressure in the brake pipe is connected to, and can be controlled by, the EPV. When moved to its "out" position, the EPV is cut out of service, and is incapable of effecting any control on the brake system. This emergency cut-out valve is sealed, and is not intended to be operated except under emergency conditions.

The emergency application valve EAV, 65 comprises a casing 40, having a chamber 41, and another chamber 42, and interconnected valve 43 and piston 44, together with a biasing spring 45. With the emergency application valve in a cab which is cut "in," as is cab A, brake pipe pressure exists in chambers 42 and 41, and due to the excess area of valve 44, over valve 43, and the spring 45, valve 43 is maintained on its seat

so as to disconnect the brake pipe 46 from atmosphere through valve passage 47.

The power-off relay POR, comprises a cover 48, in which are fixed contacts 49, which coat with movable contacts 50, carried on a stem 51, to which is connected a piston 52, operating in a cylinder 53. This cylinder 53 is in communication with pipe 3, and the piston is biased downwardly by a spring 54, in the direction to open the contacts.

10 Connected to the space outside of cylinder 53 is a pipe 55, communicating with a pressure reservoir 56. The piston (Fig. 1C) is supplied with piston rings 57 and cooperates with a sealing gasket 58 for a purpose to be described below. In 15 the sides of cylinder 53, at the upper end, are ports 59, which at times communicate with a passage 60 in stem 51, which passage 60 terminates, at its upper end, in two branches 61, each one adjacent the place where a fixed and a 20 movable contact bears against each other.

The brake pipe BP, and the main reservoir pipe MR, are supplied, respectively, with valves 62 and 63, which are to be manually operated, upon two cars being coupled, to move their 25 through ports in line with the pipes they control.

The check valve 11, can be of any usual construction, and functions, when the brake pipe cut-out valve is in its "out" position, to prevent leakage of pressure from the equalizing reservoir, back 30 into the brake pipe under unusual conditions, such as with the brake pipe cut-out valve in "off" position, RPV picked up, and the brake valve in release position, instead of in handle off position as it should be.

35 To summarize what has been explained above, with regard to the equipment on each cab, with cab A cut into service by means of its brake pipe cut-out valve, and with cab B cut out of service by means of its brake pipe cut-out valve, together 40 with proper operation of the directional switches, it may be helpful to consider the conditions existing.

In Fig. 1, with regard to cab A, the engineer's 45 brake valve EBV is shown with its handle in "service" position, and the master controller MC has been shown with its handle in its "off" position. However, they have been so shown for facilitating explanation below, and it should be 50 borne in mind that under normal operation, the engineer's brake valve is in the position shown in Fig. 2, that is, with its handle in "release" position; and the master controller has its handle in the "on" position, whereby to move drum 23, 55 so that contact segment 24 makes contact with the contacts 64, so as to complete the propulsion circuit.

In this cab A, with the brake pipe cut-out valve, as shown, in its "in" position, the engineer's 60 brake valve is connected to the brake pipe so that the valve can be operated to reduce pressure in the brake pipe and apply the brakes in the usual manner. The main reservoir is connected, by means of pipes MR and 65, to the chamber 66 in 65 the brake valve lying above the rotary valve 67.

In this "in" position, the EPV is energized, whereby to hold its valve 30 in its lower position, so as to close off the port 31 leading to atmosphere and to interconnect passages 9 and 7 so as 70 to put brake pipe pressure in chamber 41 of the emergency application valve EAV.

The suppression relay SR has its pipe 39 connected to the adapter E, and thence by way of passages 66^a and 67^a, to the equalizing reservoir, 75

whereby to compress the spring 35 to permit the closure of contacts 33-34, so that the suppression circuit, as will be more clear from the following, is closed.

5 The power-off relay POR, has its pipe 3 connected, through the brake pipe cut-out valve, to receive brake pipe pressure, whereby to close its contacts, and complete the propulsion control circuit through the master controller MC.

10 In cab B, where the brake pipe cut-out valve is in the "out" position, the engineer's brake valve is blanked off from the brake pipe by portion 15¹.

15 The suppression relay SR¹ has its pipe 39¹ connected to the adapter E and thence through passages 66¹ and 67¹ to atmosphere, whereby to open the suppression circuit, as will appear clear, below.

20 The power-off relay POR¹ has its pipe 17¹ connected through the brake pipe cut-out valve, to atmosphere, whereby its contacts are open, and the propulsion circuit is therefore open, as will appear clear, below.

25 The EPV¹ has its winding 27¹ deenergized due to the operation of the directional switch on this cab to the "Cut Out" position, and hence the chamber 81 is connected to atmosphere, while passage 9¹, carrying brake pipe pressure, is blanked off from passage 7¹. As a result, the emergency application valve EAV¹ momentarily 30 opens, but the pipes 46¹ and 68¹, leading to the passageway 69¹ of the engineer's brake valve EBV¹, is blanked off by the rotary valve 67, and hence air pressure is not lost through the emergency application valve.

35 Thus, in the cab B, which is cut out of service, control of the brakes is taken away from the engineer's brake valve, as likewise is control of the brakes taken away from the master controller and the electro-pneumatic valve, and the power-off relay is connected to atmosphere to cause it to open its contacts.

40 While running with the engineer's brake valve in "release" position, air pressure from the main reservoir passes through pipes MR and 65, to cavity 66 in the brake valve above the rotary valve 67. In this "release" position, as shown in Fig. 2, it can be seen that this pressure passes through passage 70 to charge the brake pipe BP, through passage 71 to charge the "Equalizing 45 reservoir", and through passages 71 and 72 to charge the chamber 73 above the reduction limiting valve 74. At the same time, the "Reduction limiting reservoir", and the chamber 75 beneath this valve, which are constantly interconnected by passages 76, 77 and 78, are connected by passages 79 and 80, to the passage 67¹ leading to atmosphere ATM. Also pipe 39, leading from the suppression relay SR communicates with atmosphere through passages 66¹, 81 50 and 67¹.

55 As can be readily understood from Fig. 1D, with the brake valve handle in service position, as shown, the equalizing reservoir is connected to chamber 73 above the reduction limiting valve, 60 to pipe 39 leading to the suppression relay SR, and to atmosphere through a restricted opening 82 and the passage 67¹.

65 At the same time, main reservoir pressure in cavity 66¹ passes through opening 83 to build up pressure in the chamber 75 beneath the reduction limiting valve, and in the reduction limiting reservoir through passage 76.

70 Also in this service position, the brake pipe BR is connected, by means of pipe 13, and passages 84, 85, 86 and 87 to passage 67¹ leading

to atmosphere, whereby to produce braking in addition to the usual action of the equalizing piston.

75 As soon as pressure beneath reduction limiting valve 74 builds up sufficiently to overcome the decreasing pressure above this valve, the valve moves upwardly to thereby blank off pipe 39 leading from the suppression relay, and other pipes so as to prevent further reduction in brake pipe pressure, and in pressure in chamber 73 above valve 74, and to prevent further building up of pressure in the reduction limiting reservoir, and chamber 75 beneath valve 74.

80 It is clear from the above, that upon positioning the brake valve handle in "service" position, the suppression relay SR is operated to close its contacts 33-34, and that if the handle be returned to "lap", for example, before the reduction limiting valve 74 has operated, the suppression relay is reconnected to atmosphere, and its contacts open. However, if the handle of the brake valve be left in "service" position long enough to produce a full service brake application, which results in movement of the reduction limiting valve 74, then the handle can be returned to "lap", for example, and the suppression relay contacts will stay closed until sufficient pressure leaks out of chamber 38 to permit the spring to open them. The reduction limiting valve permits the engineer to leave the valve in service position during suppression without reducing brake pipe pressure below equalization.

85 Referring now to the essentially electric portions of the system, there is represented therein a stretch of track constituted by track rails 81, 35 on which is a vehicle, indicated by the wheels and axles 88 and 89, these two sets of wheels and axles being at the two ends of a car having the two cabs A and B.

90 The wayside apparatus for applying coded train control energy to the track rails 81 has not been shown, since it can be of the type shown, for example, in the patent to T. J. Judge, No. 2,141,535, granted December 27, 1938. This wayside apparatus provides means, as in Judge, above, for placing alternating current, of a frequency different from the usual commercial frequencies, such as 100 cycles per second, on the track rails in coded form constituted by interrupting the current periodically at various rates. 95 The particular codes involved in the present system are those having a rate of 180, 120 and 75 interruptions per minute. The system is so arranged that a car in an occupied block, and in the block immediately to the rear of an occupied block, will receive no train control energy at all; one in the second block to the rear of the occupied block, will receive the 75 rate code; in the third block to the rear of the occupied block, the 120 rate code, and in the fourth 100 block to the rear, and all the blocks to the rear thereof, the 180 rate code.

95 Furthermore, there can be various overlaps if desired, such, for example, as having two successive blocks receive the 120 rate code, similar to Judge, above.

100 Also involved in the trackway apparatus, is means for automatically operating a non-signal, or cutout relay, for cutting out train control restrictions in territory which is not signalled, and this can comprise a short section of track, or a wave wire, or loop, at the entrance to non-signalled territory, which is always supplied with coded energy at a particular rate, such, for example, as 240 per minute. This trackway ar-

angement can be in general in accordance with the patent to W. W. Wenholz, No. 1,692,361, granted November 20, 1928; or W. K. Howe, No. 1,593,553, granted July 20, 1926.

5. The car carried apparatus includes a pair of receivers 89¹ carried in front of the wheels and axle 88 of cab A, and a pair of receivers 90, carried in front of the wheels and axle 89 of cab B. Each receiver is positioned, with respect to the 10 track rails, so as to inductively pick up train control energy from the track rails, and receivers 89¹, by means of wires 91, 91¹, conducts this energy to the receiving and decoding means involved in the system. In like manner, the receivers 90 conduct the inductively received energy through wires 92, 92¹ to the receiving and decoding means.

As stated above, each cab has a directional switch Direc. Sw., which is hand operated, the 20 switch for cab B having contacts 93 and 94, which are shown in the "cut out" position, whereby to cut out the receivers 90 for cab B from communicating with the receiving and decoding apparatus. The directional switch for cab A has contacts 95 and 96, which are shown in their "cut in" position, whereby to connect the cab A receivers to the receiving and decoding circuits.

30. The receivers 90 for cab B are disconnected from the receiving circuits by contact 94 having opened its front point. Receivers 89¹, however, for cab A, which cab is cut into service, is connected to the receiving circuits by means of wires 91¹, 97, contact 93 and back point, wires 98 and 35 99, the ampli-filter 100, wires 101 and 102, contact finger 103 and back point, wires 104, 105 and 106, contact 96 and front point, wire 91, and back to the receivers 89¹.

40. The ampli-filter 100 is an amplifier and filter, and is arranged to allow only 100 cycle current to pass through it with any freedom, and amplifies the energy received by means of one or more stages of tube amplification, and can be of the general type, for example, as shown in the patent 45 to O. H. Dicke, et al., No. 1,942,138, granted January 2, 1934.

45. The out-put from ampli-filter 100 passes, by wires 107 and 108 to a full-wave rectifier 109, the out-put of which passes through an obvious circuit to a code relay CR, which follows the code, and picks up and releases as the code energy is put on and cut off, whereby to vibrate its contact fingers 110 and 111 at the same rate as the code. For example, this relay picks up and releases 180 55 times per minute when the 180 code is in force; and likewise for the other codes.

If a plurality of cars be coupled together to constitute a train, then all of the directional switches must be moved to cut-out position except 60 the one in the cab at the front of the train, and all of the brake pipe cut-out valves must be operated to the "out" positions, in order to permit the train to proceed, as is obvious from the above, and the following description.

65. When relay CR is in picked-up position, it energizes a front repeater relay CRFP, through a circuit which is obvious from the drawing, and which includes contact finger 111 and front point of relay CR. This front repeater relay is made 70 slow to release by means of a resistance 112, connected across its windings, and, as indicated in the drawings, this relay has a release time of approximately .6 second.

With relay CR in released position, and with 75 relay CRFP picked up, the 75 rate relay 75R, is

energized through a circuit including contact finger 111 and back point, and contact finger 113 and front point of relay CRFP. Relay 75R is made slow to release in the same manner as is relay CRFP, and it also has a release period of 5 about .6 second.

With relay 75R picked up, a circuit is completed for energizing its repeater relay 75RP, which includes contact finger 114 and back point of an acknowledging stick relay ASR, which is normally 10 deenergized, and contact finger 115 and front point of relay 75R. This relay 75RP, after being picked up, is stuck up through a circuit including its own contact finger 116 and front point, and the contact finger 115 and front point of relay 15 75R. Relay 75RP is slow to release, and has a release time of approximately 1.25 seconds.

A repeating forestalling relay 75FP repeats relay 75RP and is picked up through a circuit including contact finger 117 and front point of relay 20 75RP, and this relay is slow to release and has a release time of approximately 2.0 seconds.

In designating the operating times of the various relays, as above, and in the following description, it should be realized that these times are not 25 necessarily fixed, and may vary widely, so long as the relationship between the times of the various relays is maintained within limits. Accordingly, times are given for merely one set of times, in which the times bear the proper relationship for 30 proper functioning of the system.

Returning now to code relay CR, this relay, through its contact finger 110, operates a push-pull transformer arrangement, through a circuit obvious in the drawing, and including a checking 35 contact 118 and front point of relay 75R. This push-pull transformer functions as in the patent to O. H. Dicke, et al., above, for example, so as to have first one part, and then the other, of its primary energized, respectively, first in one direction and then in the other, whereby to pass coded energy through the secondary of this transformer 40 119 to tuned circuits 120, 121 and 122, which circuits are respectively tuned for energy coded at the rates of 120, 180 and 240 a minute. These 45 tuned circuits include the primaries of transformers 123, 124 and 125 respectively, the secondaries of which are connected to the in-put sides of full-wave rectifiers 126, 127 and 128. The out-put sides of these rectifiers are connected 50 across the windings respectively of the rate relays 120R, 180R and the non-signal control relay 240R, whereby these rate relays respectively pick up when codes of 120, 180 and 240 are in force.

If, for example, code at the rate of 120 a 55 minute is being received, the rate relay 120R will pick up to thereby pick up its repeater relay 120RP, by energy passing through the back point of the acknowledging relay ASR, to thereby pick up the repeating forestalling relay 120FP, which 60 is interlocked with the forestalling repeating relay 180FP.

The pick-up circuit in this case for relay 120FP includes contact finger 129 and back point of acknowledging relay ASR, contact finger 130 and 65 front point of rate relay 75R, relay winding 120RP, and contact finger 131 and front point of relay 120R.

The pick-up circuit for the 120FP relay includes contact finger 132 and back point of 180RP, and 70 contact finger 133 and front point of relay 120RP. All these relays are slow to release, as indicated, and have release times approximately as indicated.

In a similar manner, if 180 code is being re- 75

ceived the 180 rate relay 180R picks up, to there-
by pick up its repeater relay 180RP, which in turn
picks up its repeating forestalling relay 180FP.

The pick-up circuit for relay 180RP includes
5 contact finger 129 and back point, contact finger
130 and front point, wire 135, contact finger 136
and back point of 120R, and contact finger 137
and front point of 180R.

Relay 180FP is a direct repeater of 180RP and
10 is picked up through contact finger 132 and front
point of 180RP.

Here again it is seen that 180RP is interlocked
with the 120 rate group, and cannot pick up un-
less 120R is down.

15 If a car should enter non-signalled territory
and encounter a short period of code at the rate
of 240 per minute, the non-signal control relay
240R will pick up through its obvious circuit.

The various rate relays, with their repeaters,
20 and their repeating forestalling relays, which cor-
respond to the three train control codes of 75,
120 and 180, are so circuited and interlocked as
as to facilitate a code producing an effect on the
train if the code is a change to a more restrictive
25 one, but to make it more difficult to produce such
an effect if the code is a change to a less re-
strictive one.

For example, if 180 code is in effect so that the
30 180 group of relays are up, that is, 180R,
180RP and 180FP, and the code changes to a
more restrictive one, such as 120, the 120R relay
can pick up immediately through a front point
35 of 180FP, the circuit including one side of the
rectifier 126, wire 138, relay 120R, wires 139 and
140, and contact finger 141 and front point of
relay 180FP, to the other side of the rectifier.

If it were not for the 180FP relay being up it
would be necessary for the 120R relay to pick
up in response to its code, through a local cir-
40 cuit including the resistance 142, this circuit in-
cluding the rectifier 126, wire 138, relay 120R,
wire 139, resistance 142, and wire 143. This last
traced pick-up circuit for 120R, including the re-
45 sistance, decreases the sensitivity of the relay
and requires that the 120 code shall have been
in force longer, in order to have the effect of
picking up the relay.

Thus, on this change to more restrictive, namely,
50 from 180 to 120 rate, the 120 rate is facilitated
in having its effect immediately on the control
by picking 120R up through the 180FP up, and
not being under the necessity of picking up
55 through the resistance 142, as would be the case
if the change were from a 75 rate code to a 120
rate code.

From the above, it can be seen that the relays
in the 120 rate group and those in the 180 rate
60 group are interlocked so that the repeater relays
and the forestalling repeaters of each group can
be operated only so as to enforce the speed limit
peculiar to the code in force, as will appear more
clear as the description progresses.

The relays belonging to the 75 rate code are
65 not interlocked with those of the 120 and the 180
group, since the 75 group relays are energized
with all codes, as is obvious from the circuit
arrangement described above.

Considering a further change to a more re-
70 strictive condition, namely, from 120 rate to 75,
the 120 rate group of relays will release and the
75 rate relays which are already up, will stay
up and a further speed restriction will be im-
posed.

Upon traveling under the 75 rate code and
75 passing from block to block, the periods during

which current is off may be so shortened as the
receiver passes over insulating joints, as to simu-
late, for example, the 120 rate code, for a mo-
mentary period of time. In these circumstances,
it is most unlikely that the rate relay 120R will
pick up, since the pick-up circuit for 120R, which
is then available, is that through the desensi-
tizing resistance 142.

Due to other reasons there may be a momen-
tary simulation of the 120 rate code as, for ex-
10 ample, with approach control of the coders, the
code motor starts from rest and comes up to
speed in the course of a very short time, but dur-
ing this time the code passes from a zero code
rate to the rate desired. In passing, for exam-
15 ple, from 75 rate code to 180 rate code, the coder
which ultimately applies 180 rate code passes
through a period when the code appears to be
120 rate, but this is only momentary and due to
20 the resistance 142 and the circuit arrangement,
the rate relay 120R will not erroneously pick up.

On passing from the 75 rate to the 120 rate code
120R will pick up through its resistance and then
later, when 120RP has picked up, it will have
25 the resistance 142 shunted out by contact finger
144 and front point of 120FP. Thus, relay 120R
is made to pick up with difficulty, and to hold up
with ease, whereby to insure that it shall not
pick up unless it is authorized to do so by an
30 authorized code, and will not release unless it
is certain that the authorized code, which picked
it up, has been definitely changed to a different
code.

If running under 120 code and on passing from
35 block to block, the 120 rate should simulate the
180 rate, even if the 180R relay should pick up,
the other relays in this 180 group, as 180RP and
180FP could not pick up, since for them to do
so requires that 120R be down, and with 120 rate
40 code in effect 120R is up and will stay up.

It will be noted that the energy for picking up
any of the repeater or forestalling relays of the
45 75, 120 and 180 group must pass through a back
point of the acknowledging stick relay ASR.
Since, when no code is present, and operation
is in the most restrictive zone, it has been nec-
essary to acknowledge and pick up the stick re-
50 lay ASR, as will appear more clearly below, it
follows that in order to change from the most
restrictive condition to a less restrictive condi-
tion, whether it be 75 rate, 120 rate, or 180 rate,
a considerable time, amounting to several sec-
55 onds, must elapse in order that relay ASR re-
lease, before the less restrictive condition can be
set up in the cab.

Involved in this system of train control is a
speed control which includes various contacts
60 operated by a speed governor which can be driven
from the car wheels or axle and controls these
contacts to open or close, as the case may be, at
various speeds of car travel. This governor can
65 operate the contacts in any usual manner, and
can be of the type, for example, as described in
the patent to Richmond, 1,409,969, granted March
21, 1922; or the patent to C. F. Estwick, above
70 referred to.

For limiting the speed of the car there is a
series of contacts, which, in cooperation with
75 contact fingers of the various FP relays, produce
an emergency brake application if the speed be
exceeded. This group of speed control contacts
includes a contact 144, which is open when the
speed exceeds 37 miles per hour, a contact 145,
open above 27 miles per hour, a contact 146 open
above 18½ miles per hour, and a contact 147 75

- open above 12½ miles per hour. These limiting speed contacts are in series, respectively, with contact finger 148 and front point of relay 180FP, contact finger 149 and front point of relay 120FP, and contact finger 150 and front point of relay 75FP, (the contact finger 150 and front point being in multiple with contact finger 151 and front point of relay 75R), and contact finger 185 and front point of relay ASR.
- 10 There are two more series of contacts controlled by car speed, and which close above certain speeds which are slightly below the limiting speeds, in order to give warning to the engineer that he is approaching the limiting speed and hence approaching an emergency brake application unless care is taken.
- One set of such contacts includes contact 152, which closes above 35 miles per hour, contact 153, which closes above 25 miles per hour, contact 154, which closes above 16½ miles per hour, and contact 155 which closes above 10½ miles per hour, and which, when closed, and depending on the various other controlling conditions, as explained below, result in the energization of a cab signal W, in each of the cabs, to display a lunar white light, thereby to apprise the engineer that he is approaching the limiting speed.
- The other set of contacts referred to, includes contact 156, which closes above 36 miles per hour, contact 157, which closes above 26 miles per hour, contact 158, which closes above 17½ miles per hour, and contact 159, which closes above 11½ miles per hour. These last referred to contacts, when closed, and subject to other controlling contacts, result in the energization of an audible signal SA in each of the two cabs, which signal may be of any distinctive type, such as a bell, as illustrated, the bell sounding when energized.
- 40 As typical of this speed control system, it can be seen that the speed contact 144^a, which opens above 37 miles per hour and results in an emergency brake application, as will appear more clear below, is associated with the speed contacts 152, and 156, which close, respectively, above a speed of 35 miles and 36 miles per hour. Thus, when operating under the 180 code, whereby to have relay 180FP up, so that a speed limit of 37 miles per hour is imposed on the car, should the engineer exceed the authorized speed of 35 miles per hour, speed contact 152 closes, to thereby energize the lunar white cab signal W, and apprise the engineer that he is approaching the speed limit. Upon the speed continuing to increase, to exceed 36 miles per hour, speed contact 156 closes, to thereby sound the audible signal SA, and apprise the engineer that he is still more closely approaching the speed limit.
- 60 In the same manner as above, when operating under 120 rate code, 75 rate code, and under no code, the speed limits of 27, 18½ and 12½ miles per hour, are set up and the limiting speed contacts 145, 146 and 147 are in force, and cooperative, respectively, with the authorized speed contacts and the warning speed contacts 153—157, 154—158 and 155—159.
- 70 It can be seen from the above that when running under any particular code, the code responsive relays thereunder determine a limiting speed by means of the FP relays and operate an authorized and warning signal by means of the RP relays, the limiting speed being such, because, if this speed be exceeded, subject to suppression, as described below, the relay EPVR 75 will become deenergized, to thereby deenergize

the electro-magnetic valve EPV and produce an emergency brake application.

In each of the cabs is a cab signal which can display various aspects. Considering the signal in cab A, it can be seen that this signal includes, in addition to the lunar white signal W, which is lighted when the authorized speed is exceeded, and the audible bell signal SA, which is sounded when the warning speed is exceeded, an audible acknowledging signal AA, which may be a buzzer, or something distinctive from the bell signal SA, and which, as will appear below, is energized and sounds when acknowledging should be performed. There is also a signal V, which, when energized, shows a violet light, for example, and is energized when operation is occurring in non-signaled territory and the non-signal relay NSR has been energized in order to relieve the vehicle from signal and speed control.

In addition to the above, the cab signal includes four signals G, Y/G, Y, R, which increase in restrictiveness, in the order named, and may also be designated by authorized speeds, as, respectively, 35, 25, 16½ and 10½, and are energized, respectively, when operating in territory having 180 code, 120 code, 75 code and no code.

The relay EPVR, which is normally energized, and which, upon becoming deenergized, causes an emergency brake application, is energized normally through one or more of several multiple circuits, in accordance with the territory through which the car is passing.

Assume that the 180 code is being received and that the speed is not above 37 miles per hour. Relay EPVR is energized through a stick circuit including its contact finger 160 and front point, contact finger 148 and front point of relay 180FP, and the limiting speed contact 144^a. If the 75 code is being received, the energizing circuit passes through contact finger 160 and front point, contact finger 150 and front point of relay 75FP, and the limiting speed contact 146, whereby the speed limit is 18½ miles per hour, instead of 37 miles per hour, since under 75 code, both the contact fingers 148 and 149 of relays 180FP and 120FP respectively, are open.

Assume, with the 180 code in effect, and hence a 37 mile speed limit imposed, that the car shall exceed 35 miles per hour, whereby to close speed contact 152, and thus energize the authorized speed warning signal W, through a circuit including contact finger 161 and back point of relay NSR, wires 162, 163 and 164, speed contact 152, wire 165, contact finger 166 and front point of relay 180RP, and wires 167 and 168.

Assume now that the speed increases to 36 miles per hour, whereupon speed contact 156 closes to thereby energize the audible bell signal, or warning signal, SA, through a circuit including contact finger 161 and back point, wires 162, 163 and 169, speed contact 156, wires 170, contact finger 171 and front point of relay 180RP, and wires 172 and 173.

Assume now, despite the warnings, the speed continues to increase, so as to be not less than 37 miles per hour, whereupon speed contact 144^a opens to open the stick circuit for relay EPVR, whereupon it releases its contact finger 174, breaking the energizing circuit for the EPV for cab A, which circuit includes the winding 27 of EPV, wire 175, directional switch contact 176 of cab A and front point, wire 177, EPVR, contact finger 174 and front point, wire 178, directional switch contact 179 of cab B and back point.

Upon the EPV of cab A becoming deenergized, the springs 28 and 29 cause the valve to vent chamber 41 of the emergency application valve EAV, to atmosphere, through port 31 of EPV, whereupon valve 43 raises from its seat to vent the brake pipe to atmosphere through port 47, and thus produce an emergency brake application.

If the warning had been heeded by the engineer before he reached the speed limit of 37 miles per hour, and he had moved his engineer's brake valve handle to service brake application position, as shown in Fig. 1D, and had moved his master controller handle to the "off" position, as in Fig. 1, a suppression circuit would have been completed for maintaining relay EPVR energized regardless of the opening of the speed contact 144. However, with the brakes applied, the speed would not have even momentarily reached the limit of 37 miles per hour unless operating on a down grade.

The suppression circuit referred to for energizing relay EPVR, including wire 180, contacts 33 and 34 of the suppression relay SR in closed position, wire 181, contacts 25 of MC in their closed position, wire 182, cab A, directional switch contact 183 and front point, wire 184^a, contact finger 185^a and front point of EPVR, wire 220, and the winding of EPVR. This suppression circuit includes a front point of the relay EPVR and hence is effective only if completed before EPVR releases.

With EPVR held up, the contact finger 174 remains up, and thus the deenergization of the EPV for cab A is prevented, and thus the emergency brake application is forestalled.

Assume now that while operating under 180 code, at a speed of perhaps 34 miles per hour, the code changes to the 120 rate, whereby to cause the 180 group of relays to release and the 120 group of relays to pick up. Upon the release of the 180 group relay 180RP, its contact fingers 166 and 171 make up their back points. Since, at this time, the 120 group relay 120RP is already up, so that its contact fingers 184, 183 are making up their front points, and since the speed is high enough for the speed contacts 153 and 157 to be closed, circuits will be completed for the authorized speed warning signal W, and the warning speed signal SA, through circuits which are obvious from the drawing, to thereby apprise the engineer that his speed is excessive and that he must act promptly to forestall an emergency brake application.

Upon the release of relay 180RP, which gives the warning to the engineer, relay 180FP is de-energized, to release two seconds thereafter, and thereby deenergize relay EPVR, unless the speed be below 27 miles per hour, and upon deenergization EPVR releases .5 second thereafter, to produce an emergency brake application as explained above. During this period of time of sequential release of 180FP and EPVR, amounting to 2.5 seconds, the engineer can forestall the emergency brake application by moving his engineer's brake valve handle to service brake application position and moving his master controller handle to the "off" position, whereby to complete the suppressive braking circuit traced above, and forestall the emergency brake application.

Assuming the engineer acts promptly the emergency brake application is forestalled and upon the speed being reduced below 25 miles per hour the signals W and SA are both deenergized

and the engineer knows that he is within safe speed limits and can release his brakes and operate his master controller handle as he desires.

In other changes from one code to another, the conditions outlined above are similar and the requirements are similar. It is to be understood, of course, that, when going from one condition to a less restrictive condition, there is no occasion for action on the part of the engineer, because his speed limit, in that case, instead of being suddenly reduced, is suddenly increased, thus, to allow him even wider latitude in the operation of his car.

We can now assume that after operating in territory where 75 rate code is being received, and the speed is maintained under 18½ miles per hour, territory is entered in which no code is present. In these circumstances the 75 rate group of relays all release and upon the release of 15FP, a speed limit of 12½ miles per hour is imposed on the car. Since none of the FP relays is energized, the energy for relay EPVR passing through its contact finger 160 and front point cannot reach the relay and it is necessary to receive energy for the relay EPVR over wire 184^b and contact finger 185 and front point of the acknowledging stick relay ASR. Not only is this necessary but it is also necessary that the speed be within 12½ miles per hour in order that speed contact 147 shall be closed.

Hence, under these conditions, if the speed be above 12½ miles per hour, which may, of course, be the case, it is necessary to have recourse to suppressive braking, as described above, and then before the suppressive braking is discontinued to operate the acknowledging contactor Ack. C., in order to pick up the acknowledging stick relay ASR.

Assuming that suppressive braking has been accomplished, if necessary, and that the speed is not above 12½ miles per hour whereby speed contact 147 is closed, we can next assume that the acknowledging contactor is operated.

Under the conditions assumed, the back repeater relay BPR is up. This relay picks up through any one of the three contact fingers 186 of relay 15R, 187 of relay CRFP, and 188 of relay EPVR, and their back points, these contacts all being in multiple, and the two acknowledging contactors 189 and 190 for the cabs B and A, and their front points, in series. The pick-up circuit for BPR therefore includes acknowledging contact 190 and front point, contact finger 186 and back point, the winding of BPR, wire 191, and acknowledging contact 189 and front point.

When up, BPR sticks up independently of the acknowledging contacts, but dependent upon back points of the acknowledging stick relay ASR, through a circuit including contact finger 192 and back point of ASR, contact 193¹ and back point of BPR, contact 186 and back point of 15R, the winding of BPR, contact finger 193 and front point of BPR, and contact finger 192¹ and back point of ASR.

The occasion for acknowledging has been brought to the attention of the engineer in a forcible manner by the sounding of the signal AA, which is audible, and may be a buzzer or the like, and at least of a type to be distinguished from the bell SA. With no codes present, these signals AA, in each of the two cabs, are energized through a circuit including contact finger 194 and back point of relay NSR, contact finger 195 and back point of relay 15RP, contact fin-

ger 196 and front point of BPR, contact finger 197 and back point of ASR, and the wire 198.

On hearing the buzzer AA the engineer realizes that acknowledgment must be performed before the suppressive braking has been released, or otherwise the relay EPVR will become deenergized and produce an emergency brake application. The engineer therefore depresses the acknowledging contactor of his cab (B), which is pedal operated, to thereby pick up acknowledging stick relay ASR through a circuit including acknowledging contact 199 and back point, contact finger 200 of relay BPR and front point, contact finger 201 and back point of NSR, contact finger 202 and back point of 240R, wire 203, and the winding of ASR.

After being picked up, relay ASR sticks up through a circuit including contact finger 204 and front point of ASR, contact finger 205 and front point of BPR, contact finger 206 and front point of EPVR, and contact finger 207 and back point of NSR.

It is necessary that the acknowledging contactor be promptly returned to its normal position since the picking up of relay ASR has broken the stick circuit for relay BPR and the pick-up circuit of relay BPR is dependent upon the acknowledging contactor being positioned in its normal position so as to close contact 189 on its front point. Unless the acknowledging contactor be promptly returned, the picking up of relay ASR deenergizes relay BPR which releases to thereby break both the pick-up and stick circuits of BPR, which then releases its contact finger 185, and deenergizes relay EPVR, with an emergency brake application as the result.

If, however, the engineer properly returns the acknowledging contactor, acknowledging stick relay ASR stays up and with the speed not exceeding 12½ miles per hour, relay EPVR remains energized through a circuit including wire 184, contact finger 185 and front point, and the various speed contacts 141, 146, etc. in series, to thereby prevent emergency brake application.

After acknowledgment, as described above, the engineer may proceed within the 12½ mile speed limit so long as the danger or no-code conditions exist. As soon as any code is received, the rate relay 75R, for example, will pick up to thereby drop the back repeater relay BPR, which in turn will drop the acknowledging stick relay ASR. It is only after these two relays have released that energy through contact finger 114 of relay ASR is available to pick up the RP and FP relays under the 75 rate group and set up a speed limit of 18½ miles per hour and remove the operation from the danger (acknowledgment) condition. Since these relays BPR and ASR are slow to release, it can be seen that several seconds elapse after a code has been received before it sets up its particular speed limit, and thus it is assured that operation in red territory will not be mistakenly discontinued by any temporary pulsating energy on the track rails, as a transient code or such as to momentarily simulate a code.

It was described above that at times the car may operate in territory which is not signaled, and in which there is no trackway apparatus for applying coded train control current to the track rails. In order to permit the engineer to proceed on his own initiative, and free from the restrictions which such conditions place constantly on the car, the entrance to each such zone is provided with a loop, or a short track

section, as above described, to which coded current at the rate of 240 per minute is applied.

Let us assume that the car enters such a territory, and upon encountering the 240 code, relay 240R picks up as described above. With 5 relay 240 up, relay NSR picks up through a circuit including wire 208, contact finger 209 and front point of relay 15R, contact finger 210 and back point of relay ASR, contact finger 211 and front point of 240R, and the winding of relay 10 NSR.

Upon leaving the 240 loop, relay 240R releases, as also does relay 75R. The release of relay 75R causes the back repeater relay BPR to pick up, whereupon a stick circuit is completed for relay 15 NSR which includes contact finger 212 and front point of relay BPR, contact finger 213 and front point of NSR, contact finger 214 and front point of EPVR, contact finger 211 and back point of 240R, and the winding of NSR.

With relay NSR up, contact finger 103 of this relay is picked up, whereby to include a variable resistance 215 in the receiving circuit passing to the ampli-filter, and thus to reduce the sensitivity of the receiving circuit while traveling in 25 NS territory so as to further assure that no unauthorized pulses of current will have any effect on the car carried apparatus.

Also, with relay NSR up contact finger 194 thereof is up, to thereby break the circuit for 30 energizing the acknowledging signal AA, so as to prevent this signal from sounding. Also, with contact finger 216 of relay NSR in its picked up position, the energy for the signals G, Y/G, Y and R, which passes through a back point of this 35 finger, is removed from these signals, and this energy passes through the front point of 216 and wire 217 to energize the signal V, which can display, when energized, a violet light, to indicate to the engineer that he is traveling in NS 40 territory.

Under NS conditions, as described above, relay EPVR is directly held up through contact finger 161 of NSR and front point and wires 218, 219, 220, etc., whereby to avoid any deenergization of the EPV, with a resulting brake application.

It will be noted that the stick circuit for relay NSR includes a front point of back repeater relay BPR, and accordingly, shortly after a code is received, relay BPR will release to thereby cause NSR to release, and bring the car under speed control, in accordance with the particular code enforced.

An additional condition sometimes exists which must be cared for, and occurs where a car may be cut into service while in NS territory, and hence the car cannot experience a period of 240 code, to set up NS conditions. To care for this situation, the NSC or non-signal contactor has been provided. Under the conditions assumed, that is, no code in force, the acknowledging signal AA will sound by virtue of the circuit traced above. To silence this signal, the acknowledging contactor will be depressed, and then restored to its normal position, to thereby pick up and 65 stick up acknowledging stick relay ASR.

Also, with relay ASR up, and the speed not above 12½ miles per hour, relay EPVR is picked up and held up.

The NS contactor NSC will then be operated, 70 this contactor being relatively inaccessible, and operable by the brake valve handle, which can be removed from the brake valve only after having been turned to a position to have first produced a full service brake application. Opera- 75

tion of contactor NSC picks up relay 240R through a circuit including directional switch contactor 218 and front point, NSC contactor 219 and back point, contact finger 220 and back point 5 of relay 15R, and the winding of relay 240R.

With 240R up, the acknowledging stick relay ASR up, a pick-up circuit is completed for relay NSR which includes contact finger 218 and front point, contact finger 219 and back point, 10 contact finger 210 and front point of relay ASR, contact finger 211 and front point of relay 240R, and the winding of NSR.

Upon the release of contactor NSC, relay 240R releases, and with relay EPVR up, a stick circuit 15 is completed for relay NSR which includes contact finger 212 and front point of relay BPR, contact finger 213 and front point of relay NSR, contact finger 214 and front point of relay EPVR, and contact finger 211 and back point of 20 relay 240R.

It is necessary to return the NS contactor to its normal position, and thus cause the energization 25 of NSR to depend upon the above traced stick circuit, since if an attempt were made, after operating the NS contactor, to leave it in operated position, the continued picked up condition of NSR would break the stick circuit for relay ASR at contact finger 207 and back point, whereupon relay ASR would release, and break 30 the pick-up circuit for relay NSR at contact finger 210 and front point, whereupon relay NSR would release and the operation of the NS contactor would have produced no result.

Upon the train leaving NS territory and entering 35 coded territory, various of the code responsive relays will pick up, and since any code will pick up relays CRFP and 15R, this will cause back repeater relay BPR to release to thus break the stick circuit for relay NSR, and restore the car 40 to speed control in accordance with the code in force. This restoration occurs only a considerable time after the code has been first received, since, before the car is restored to speed restrictions, it is necessary that enough time 45 elapses for the sequential release of slow release relay BPR, and slow release relay NSR, or a matter of about 5½ seconds.

The back repeater relay BPR, is also up, when 50 relay EPVR is down, and this provides a means for resetting after incurring an emergency brake application, by means of the acknowledging contactor Ack. C.

Assume, for example, that when traveling under a speed limit of, for instance, 27 miles per 55 hour, that is, under the 120 code, the speed exceeds the 27 mile limit to cause the deenergization of EPVR and a resulting emergency brake application. In order to reenergize EPV, and permit the car to proceed, it is necessary first to 60 reduce the speed to at least 12½ miles per hour, whereby to close all of the speed limit speed contacts 141, 146, etc., and then to acknowledge so as to close the resetting circuit for relay EPVR at contact finger 185 and front point of acknowledging stick relay ASR. Since acknowledgement 65 requires that relay BPR be picked up, and since in coded territory, this would not be the case except for contact finger 183 and back point of relay EPVR being in the pick-up circuit or relay BPR, it follows that this provision is what makes 70 resetting possible in this system by use of the contactor Ack. C.

From the above it can be realized that an improved complete system of inductive train control, 75 embodying acknowledgment, resetting, sup-

pressive braking, and operation in non-signaled territory, has been provided.

The above rather specific description of one form which this invention can assume, has been given solely by way of example, and not, in any way, in a limiting sense. It should be understood that this specification contemplates covering all such variations and modifications as may, from time to time, occur, so long as they are not specifically excluded from the invention by reasonable interpretation of the appended claims.

Having described our invention, we now claim:

1. In a coded train control system, in combination, car carried means including a receiver positioned to receive train control energy from the trackway, decoding means responsive to energy in the receiver to impose one limit when the energy is coded and a lower limit when the energy is non-coded, normally inactive brake control means effective, upon an imposed limit being exceeded, to become active and cause an automatic brake application, an acknowledging relay, an acknowledging contactor positionable either normal or reverse, a slow release repeater relay having a pick-up circuit closed when no code is present and the acknowledging contactor is normal, a stick circuit for the repeater relay closed when no code is present and the acknowledging relay is in released position, an energizing circuit for the acknowledging relay including the contactor in reverse position and a front point of the repeater relay, a stick circuit for the acknowledging relay independent of the contactor and closed only if no code be present, and a circuit for making the brake control means inactive and including a front point of the acknowledging relay, whereby the acknowledging contactor must be promptly returned from its reverse to its normal position.

2. In a coded train control system, in combination, car carried means including a receiver positioned to receive train control energy from the trackway, decoding means responsive to energy in the receiver to impose one limit when the energy is coded and a lower limit when the energy is non-coded, normally inactive brake control means effective upon an imposed limit being exceeded to become active and cause an automatic brake application, an acknowledging relay, an acknowledging contactor positionable either normal or reverse, a slow release repeater relay having a pick-up circuit closed when no code is present and the acknowledging contactor is normal, a stick circuit for the repeater relay closed when no code is present and the acknowledging relay is released, an energizing circuit for the acknowledging relay including the contactor in reverse position and a front point of the repeater relay, a stick circuit for the acknowledging relay independent of the contactor and closed only if no code be present, a circuit for making the brake control means inactive and including a front point of the acknowledging relay, whereby the acknowledging contactor must be promptly returned to its normal position, and another pick-up circuit for the repeater relay requiring, when closed, that the acknowledging contactor be normal and the brake control means be active, whereby the acknowledging contactor can function as a reset means.

3. In a coded train control system, in combination, car carried means including a receiver positioned to receive train control energy from the trackway, decoding means responsive to energy in the receiver to impose one limit on the train

- operation when the energy is coded and a lower limit when the energy is non-coded, normally inactive brake control means effective upon an imposed limit being exceeded to become active and cause an automatic brake application, an acknowledging relay, an acknowledging contactor positionable either normal or reverse, a slow release repeater relay having a pick-up circuit closed when no code is present and the acknowledging contactor is at normal, a stick circuit for the repeater relay closed when no code is present and the acknowledging relay is at released, an energizing circuit for the acknowledging relay including the contactor at reverse and a front point of the repeater relay, a stick circuit for the acknowledging relay independent of the contactor and closed only if no code be present, and a circuit for making the brake control means inactive and including a front point of the acknowledging relay, whereby the acknowledging contactor must be promptly returned to its normal position, and a penalty means made active by the absence of code, and made inactive by the energization of the acknowledging relay.
25. 4. In a coded train control system, in combination, car carried means including a receiver positioned to receive train control energy from the trackway, decoding means responsive to energy in the receiver to impose one limit when the energy is coded and a lower limit on train operation when the energy is non-coded, normally inactive brake control means effective, upon an imposed limit being exceeded, to become active and cause an automatic brake application, an acknowledging relay, an acknowledging contactor positionable either normal or reverse, a slow release repeater relay having a pick-up circuit closed when no code is present and the acknowledging contactor is at normal, a stick circuit for the repeater relay closed when no code is present and the acknowledging relay is released, an energizing circuit for the acknowledging relay including the contactor at reverse and a front point of the repeater relay, a stick circuit for the acknowledging relay independent of the contactor and closed only if no code be present, and a circuit for making the brake control means inactive and including a front point of the acknowledging relay, whereby the acknowledging contactor must be promptly returned to its normal position, the acknowledging relay being slow to release, whereby, the sum of the successive release times of the repeater relay and the acknowledging relay must elapse after code is initiated, before the said one limit is imposed.
5. In a coded train control system, in combination, car carried means including a receiver positioned to receive train control energy from the trackway, decoding means responsive to energy in the receiver to set up a speed limit for energy coded at one rate, a non-signal relay energized by the response of the decoding means to energy coded at another rate, a normally energized brake control relay effective, when deenergized, to cause an automatic brake application, a pick-up circuit for the brake control relay including a front point of the non-signal relay, a stick circuit for the brake control relay opened if an imposed speed limit be exceeded, an acknowledging contactor positionable either normal or reverse, a slow release acknowledging relay the energized condition of which is dependent upon the contactor being at reverse, a directional switch operable to "in" position to connect the receiver to the decoding means, an N. S. contactor positionable either nor-

mal or reverse, a circuit for picking up the non-signal relay requiring for its closure the directional switch to be in its "in" position, the N. S. contactor at reverse and the acknowledging relay picked up, and a stick circuit for the non-signal relay requiring for its closure the N. S. contactor to be at normal, the acknowledging relay being dependent for its energization on a back point of the non-signal relay, whereby the N. S. contactor must be promptly returned to its normal position. 10

6. In a coded train control system, in combination, car carried means including a receiver positioned to receive train control energy from the trackway, decoding means responsive to energy in the receiver to impose a speed limit on the train operation for energy coded at one rate, a non-signal relay energized by the response of the decoding means to energy coded at another rate, a normally energized brake control relay effective, when deenergized to cause a brake application, a pick-up circuit for the control relay including a front point of the non-signal relay, a stick circuit for the control relay opened if an imposed speed limit be exceeded, an acknowledging contactor positionable either normal or reverse, a slow release acknowledging relay having an energizing circuit closed only if the contactor be in reverse, a directional switch operable to "in" position to connect the receiver to the decoding means, an N. S. contactor positionable either normal or reverse, a circuit for picking up the non-signal relay requiring for closure that the directional switch be in its "in" position, the N. S. contactor at reverse and the acknowledging relay picked up, and a stick circuit for the non-signal relay requiring for closure that the N. S. contactor be at normal, the acknowledging relay being dependent for its energization on a back point of the non-signal relay, whereby the N. S. contactor must be promptly returned to its normal position, a slow release repeater relay, an energizing circuit for the repeater relay requiring, to be closed, that no coded energy be received, the stick circuit for the non-signal relay including a front point of the repeater relay, whereby non-signal control is removed by receipt of coded energy only after the occurrence of the sequential release of the repeater relay and the non-signal relay. 30

7. In a coded train control system, in combination, car carried means including a receiver positioned to receive train control energy from the trackway, decoding means responsive to energy in the receiver to set up a speed limit for energy coded at one rate, a non-signal relay energized by the response of the decoding means to energy coded at another rate, a normally energized brake control relay effective, when deenergized to cause a brake application, a pick-up circuit for the brake control relay including a front point of the non-signal relay, a directional switch operable to "in" position to connect the receiver to the decoding means, and a variable, desensitizing means controlled by the non-signal relay and inserted in the connection between the receiver and the decoding means when the non-signal relay is energized. 50

8. In a coded train control system, in combination, car carried means including a receiver positioned to receive train control energy from the trackway, decoding means responsive to energy in the receiver to impose limits on train operation according to the code, a brake control relay effective when deenergized to apply the brakes, a master controller for control of car 70

propulsion current, an engineer's brake valve, a directional switch movable to "in" position to connect the receiver with the decoding means, means for deenergizing the brake control relay 5 upon exceeding a limit imposed on the car, and a suppression energizing circuit for the brake control relay closed only upon cutting off propulsion current by the master controller, positioning the directional switch to its "in" position and 10 operating the brake valve to its "service" position.

9. In a coded train control system, in combination, car carried means including a receiver positioned to receive train control energy from the trackway, decoding means responsive to energy 15 in the receiver to impose limits according to the code in force, a brake control relay effective when deenergized to apply the brakes, a master controller for control of car propulsion current, an engineer's brake valve, a directional switch movable to "in" position to connect the receiver with the decoding means, means for deenergizing the control relay upon exceeding an imposed limit, a suppression energizing circuit for the control relay closed only upon cutting off propulsion current 20 25 rent by the master controller, positioning the directional switch to its "in" position, and operating the brake valve to "service" position, and means to maintain the suppression circuit closed after the brake valve has been moved to non-braking position only if a full service brake application has first been effected.

10. In train control systems, in combination, a propulsion power circuit, a power off relay to control the circuit, the relay including, a casing, 30 a cylindrical chamber in the casing, a contact chamber in the casing, a piston fitting the cylindrical chamber and slidable therein, a stem on the piston extending into the contact chamber, a contact carried by the stem, a coacting fixed 35 contact in the contact chamber, means biasing the piston to open the contacts, a source of fluid pressure connectable to the piston chamber beneath the piston to move it to close the contacts, a pressure reservoir, a constricted passage at all 40 times connecting the cylinder chamber to the reservoir, a non-constricted passage connecting the reservoir to the space above the piston, and a sealing means effective to close the non-constricted passage only when the piston is operated 45 by pressure to its extreme position.

11. In train control systems, in combination, a propulsion power circuit, a power off relay to control the circuit, the relay including, a casing, a cylindrical chamber in the casing, a contact 50 chamber in the casing, a piston fitting the cylindrical chamber for sliding therein, a stem on the piston extending into the contact chamber, a contact carried by the stem, a coacting fixed contact in the contact chamber, means biasing the piston to open the contacts, a source of fluid pressure connectable to the piston chamber beneath the piston to move it to close the contacts, a pressure reservoir, a constricted passage connecting the cylinder chamber and the reservoir 55 at all times, a non-constricted passage connecting the reservoir to the space above the piston, a sealing means effective to close the non-constricted passage only when the piston is fully operated by pressure, and a pressure blow-out 60 passage in the stem, connected at one end to the space above the piston and at the other end terminating adjacent the contact carried by the stem for extinguishing arcs.

12. In a train control system; a car; a cab at 75 each end of the car; a receiver for each cab and

positioned in association with the trackway to receive control energy therefrom; decoding means on the car responsive to energy in the receivers when connected thereto; a directional switch in each cab and movable to "in" position to connect its receiver to the decoding means; an engineer's brake valve, an emergency application valve, and a brake pipe cut-out valve which latter is movable to "in" or "out" position, in each cab; means, when a cut-out valve is at 10 "in" position, to connect the brake valve and application valve with brake pipe pressure, and when at "out" position to cut them off therefrom; a normally energized brake control means in each cab and effective, when its cab is cut "in" 15 to cause operation of the application valve and apply the brakes, if it becomes deenergized; and an energizing circuit for each brake control means requiring, for closure, that its directional switch be at "in" position, and the other directional 20 switch be at "out" position.

13. In a train control system; a car; a cab at each end of the car; a receiver for each cab and positioned in association with the trackway to receive control energy therefrom; decoding means 25 on the car responsive to energy in the receivers if connected thereto; a directional switch in each cab and movable to "in" position to connect its receiver to the decoding means; an engineer's brake valve, an emergency application valve, and a brake pipe cut-out valve which is movable to "in" or "out" position, in each cab; means effective, when a cut-out valve is at "in" position, to connect the brake valve and application valve with brake pipe pressure, and when at "out" position to cut them off therefrom; a brake control means in each cab and effective, when its cab is cut "in", to cause operation of the application valve and thereby apply the brakes, if it becomes deenergized; an energizing circuit for each brake 40 control means closed only when its directional switch is at "in" position; and the other directional switch is at "out" position, a master controller in each cab to control car propulsion current, and means whereby operation of the application 45 valve is effected unless the controller handle is held by the engineer in any operative position except its power-off position.

14. In a train control system; a car; a cab at each end of the car; a receiver for each cab and positioned adjacent the trackway to receive control energy therefrom; decoding means on the car responsive to energy in the receivers if the latter are connected thereto; a directional switch in each cab and movable to "in" position to connect 55 its receiver to the decoding means; an engineer's brake valve, an emergency application valve, and a brake pipe cut-out valve which is movable to "in" or "out" position, in each cab; means effective, when a cut-out valve is at "in" position, 60 to connect the brake valve and application valve with brake pipe pressure, and when at "out" position to cut them off therefrom; a brake control means in each cab and effective, when its cab is cut "in", to cause operation of the application valve and apply the brakes, if it becomes deenergized; an energizing circuit for each brake control means closed only when its directional switch is at "in" position and the other directional switch is at "out" position; a master controller 70 in each cab to control car propulsion current; means whereby operation of the application valve is produced unless the controller handle is held by the engineer in any operative position except its power-off position; a power-off relay in each 75

- cab controlling car propulsion current for its cab; and pressure means to close the relay contacts when the cut-out valve is at its "in" position.
15. In a train control system, a brake valve, 5
brake control means effective when deenergized to apply the brakes, a suppression energizing circuit for the brake control means, a suppression relay controlling the suppression circuit, and pressure responsive means for operating the suppression relay to close the suppression circuit which includes an equalizing reservoir and a reduction limiting reservoir respectively connected to the space above and below the reduction limiting valve of the brake valve, means operative 10
15 when the brake valve is in "release" position, to build up pressure in the equalizing reservoir and exhaust pressure from the reduction limiting reservoir, a pipe connecting an operating chamber in the suppression relay to the brake valve 20
25 and operating to exhaust the operating chamber to atmosphere with the brake valve in "release" position, means, when the brake valve is in "service" position, to connect the equalizing reservoir to the operating chamber, and also to atmosphere through a constricted passage, and the reduction limiting reservoir to a pressure source, the reduction limiting valve moving upwardly when the pressure below it exceeds that above it, whereby to close, and maintain closed, the connection between the suppression relay operating 30
35 chamber and atmosphere, even though the brake valve be returned to "release" position.
16. In train control systems, a car carried receiver positioned to receive energy, coded at different rates, from the trackway, a decoder responsive to the energy in the receiver in a distinctive way for each code; three contacts positioned in accordance with car speed, for coacting with the decoder when responding to each 40
45 code, there being, for each code, an authorized speed limit imposed by the decoder and one of said speed contacts, a warning speed limit imposed by the decoder and a second of said speed contacts, and a limiting speed limit imposed by the decoder and the third of said speed contacts, a signal for each warning and authorized limit, means energizing the signals upon their limits being exceeded, and a brake control means effective to apply the brakes upon the limiting speed limit being exceeded.
17. In train control systems; a car carried receiver positioned to receive energy, coded at different rates, on the trackway; a decoder responsive to the energy in the receiver in a distinctive 55
60 way for each code; three contacts controlled by car speed, for coacting with the decoder when responding to each code; and circuit means for each code for causing an authorized speed limit to be imposed by the decoder and one of said speed contacts, a warning speed limit to be imposed by the decoder and a second of said speed contacts, and a limiting speed limit to be imposed by the decoder and the third of said speed contacts; a signal for each of said first two limits; 65
70 means energizing the signals upon their limits being exceeded; a brake control means effective to apply the brakes upon the limiting speed limit being exceeded; a propulsion circuit, and suppressing means for preventing the brake control

means from becoming effective and including an energizing circuit closed, only if the brakes be applied manually, and the propulsion circuit to be opened.

18. In a train control system, in combination, 5
a car carried receiver positioned to receive train control energy, variously coded to produce different degrees of restriction on train operation, from the trackway, decoding means distinctively responsive to the variously coded energy in the 10
15 receiver and to the absence thereof, the decoding means including a least restrictive relay, a more restrictive relay, and a still more restrictive relay each of which relays corresponds with a particular code and picks up on receipt of its code to 20
25 remove its restriction, means operative upon the absence of code to impose a most restrictive condition, a signal energized upon the imposition of said most restrictive condition, a manual contactor, a slow release, acknowledging relay energizable by the contactor in the absence of code to deenergize the signal, and an energizing circuit for each of the restrictive relays including a back point of the acknowledging relay.

19. In a train control system, in combination, 25
a car carried receiver positioned to receive coded train control energy, variously coded to produce different degrees of restriction on train operation, from the trackway, decoding means distinctively responsive to the variously coded energy in the 30
35 receiver and to the absence thereof, the decoding means including a least restrictive relay, a medium restrictive relay and a more restrictive relay, each of which relays corresponds to a particular one of said codes and picks up on receipt of its code to remove its restriction, pick-up energizing circuits for the restrictive relays, and means making the circuit for the medium restrictive relay more sensitive when its code is preceded by the code of the least 40
45 restrictive relay than when preceded by that of the more restrictive relay, thus to facilitate changes to more restrictive conditions and impede those to less restrictive conditions.

20. In a train control system, in combination, 45
a car carried receiver positioned to receive train control energy, variously coded to produce different degrees of restriction on train operation, from the trackway, decoding means distinctively responsive to the variously coded energy in the 50
55 receiver and to the absence thereof, the decoding means including a least restrictive relay, a medium restrictive relay and a more restrictive relay, each of which corresponds to a particular one of said codes and which picks up on receipt of its code to remove its restriction, pick-up energizing circuits for the restrictive relays, and means making the circuit for the medium restrictive relay more sensitive when its code is preceded by the code of the least restrictive relay than when preceded by that of the more 60
65 restrictive relay, thus to facilitate changes to more restrictive conditions and hinder those to less restrictive conditions, said less sensitive circuit including current limiting means, and said more sensitive circuit depending on the energized condition of said least restrictive relay.
